UNITED STATES PATENT OFFICE.

PETER BAGDON, OF KINCAID, ILLINOIS.

MINER'S DRILL.

Application filed August 22, 1922. Serial No. 583,566.

To all whom it may concern:

Be it known that I, PETER BAGDON, a citizen of Lithuania, residing at Kincaid, county of Christian, and State of Illinois, have invented certain new and useful Improvements in Miners' Drills, of which the following is a specification.

This invention relates to improvements in boring machines or drills for coal, rock and other similar substances, and particularly improvements in the drill tool and its holder.

It is the principal object of the invention to provide a drill holder adapted to ex- changeably hold a plurality of drills.

Another object of the invention is the provision of a drill of peculiar shape which will positively and effectively cut coal and rocks or the like.

20 A further object of the invention is the provision of a drill equipped with means for protecting the means for holding the drill tool in its holder.

These and other objects and advantages 25 of my invention will become more fully known as the description thereof proceeds and will then be specifically pointed out in the appended claim.

In the accompanying drawing, forming 30 a material part of my invention,

Figure 1 is a front view of a drill holder and drills constructed according to the present invention.

Figure 2 is an end view thereof.

35 Figure 3 is a rear view of drill holder and drills.

Figure 4 is a cross-section on line 4—4 of Figure 3.

Figure 5 is a detail view of one of the 40 drills, and

Figure 6 is a detail view of another of the drills.

The drill holder 10 is at one end provided with a socket 11 for attachment to the lower 45 end of the shaft of a drilling machine or the like by means of fastening means passed through the holes 12 and 13 respectively.

The front face of the holder 10 is provided with a V-shaped depression 14 having

beveled, undercut side walls adapted to be 50 engaged by the outer and upper beveled edges of the drill tools.

These tools are illustrated in Figures 5 and 6 and are designated 15 and 16 respectively, and have a substantially prismatic 55 shape showing triangular rear ends 17, 18 and beveled front ends 19 and 20. The tool 16 has a sharp chisel-like front edge 21, while with the tool 15, this edge is notched, as at 22. A block 23 with beveled side faces 60 which are adapted to engage the inner beveled side faces of the tools 15 and 16 is arranged in depression 14, and is held in place by means of a bolt 24 provided with a head 25 resting upon the upper face of block 23. 65

The opposite end of bolt 24 is screw threaded and carries a nut 26 adapted to hold parts 23, 15 and 16 in their adjusted positions. On the rear face of holder 10 a protecting fin 27 is secured as shown in Figure 3.

The operation of the device will be quite clear from the foregoing description without further explanation.

It will be clear that changes may be made 75 in the general arrangement and construction of the minor details of my invention without deviating from the scope and spirit of my invention.

What I claim as new and desire to secure 80 by Letters Patent is—

A tool holder for miners' drills, comprising a socketed body, having a depression formed in one face, the side walls of the depression being divergent toward the forward end of the body and being undercut, a block adapted to interfit with adjacent sides of two drills to hold said drills in the undercut portions of the side walls of the depression, a bolt for securing the block to 85 the body, and a nut engaging said bolt on the rear surface of the body, said body being formed with a fin extending diagonally across the body and serving to protect the nut in the use of the tool. 90

In testimony whereof I have affixed my signature.

PETER BAGDON.
